UNITED STATES PATENT OFFICE

JOHN C. HOLLAND, OF BROOKLYN, NEW YORK

DETACHABLE CUFF

Application filed July 1, 1925, Serial No. 40,911.

My invention relates to detachable cuffs and is adapted to be folded over substantially and particularly to cuffs of the fold-back type along the line 7, button-holes being provided adapted for attachment upon and detachment at 8 and 9 on one side of the fold, and the two from shirt sleeves. The fabrics 5 and 6 being separately button-holed

5 An object of this invention is to provide a cuff as at 10 and 11, on the opposite side. The fabric 6 is cut away intermediate the button-holes 10 and 11 to a depth slightly less than usual cuff-buttons or links, and which will be the width of the fold, and the edges around present substantially the same appearance as this cut-away portion are stitched down or 10 a soft folded cuff such as is now usually permanently attached upon shirt sleeves. The cutting away of the fabric leaves the flaps 12 and 13 otherwise suitably finished. This cutting

A further object resides in so constructing the cuff that the cuff end of the shirt sleeve is which are secured to the fabric 5, and the two fabrics on the remaining side of the fold 7 are entirely enclosed within the cuff and the cuff double throughout.

15 structure is maintained in a snug and neat fit. In the use of my improved detachable cuff, the shirt-sleeve cuff 2 is inserted between the

With the above and other objects in view, the fabrics 5 and 6 where the same are cut away, which will be apparent to those skilled in the art, my invention includes certain novel features of construction and combinations and arrangements of parts which will be set forth in connection with the drawings.

In the drawings:

Figure 1 is a view in elevation of the lower end of a shirt sleeve having my cuff fitted thereon.

Fig. 2 is a similar view, with the cuff link removed and the detachable cuff folded back and 9 therethrough. This cuff structure pre-

30 Fig. 3 shows the shirt sleeve and cuff opened up.

Fig. 4 is a view in elevation of the detachable cuff as it appears when folded out flat.

Fig. 5 is a sectional view on line 5—5 of

35 Fig. 4.

My detachable cuff can be made particularly for and can be marketed with a shirt as manufactured and sold, or the cuffs can be made and sold separately, to be applied to and used upon any shirt. The only essential requirement in the shirt is that the sleeves 1 shall have the lower or cuff portions 2 thereof provided with the button-holes 3 and 4.

The detachable cuff is made up of the outer

45 and inner fabrics 5 and 6, which are stitched or otherwise secured together around three of their edges, the fabrics being unattached along one of the long edges. The finished cuff is of substantially double the size of the usual turned-back portion of a folded soft cuff,

From the foregoing it will be seen that I have provided a detachable cuff which can be readily fitted upon a shirt-sleeve cuff to be held in place by the usual cuff link or button without the use of supplemental fastenings or securing of any sort; and, that the detachable cuff structure is of simple construction, readily manufactured, and is of such form that it can be folded out entirely flat for laundering and finishing.

Whilst I have herein shown and described only certain specific constructions and embodiments of my invention, it will be appreciated that changes in the form, construction and assembly of the parts can be made to suit various requirements of use, without de-

parting from the spirit and scope of my invention.

I claim:

1. A detachable cuff of the double fold type adapted for detachable application to a shirt-sleeve cuff, comprising two fabrics of cuff shape secured together along three sides and unsecured along the remaining side, one of said fabrics being cut away in its middle portion adjacent the unsecured side and both fabrics being provided with button openings to register with the button-holes of the sleeve cuff, said cut away area extending approximately from the button hole at one end of the cuff to the button hole at the other end of the cuff.

2. A detachable cuff of the double fold type for application to a shirt-sleeve cuff, comprising two layers of material of substantially cuff shape secured together on three of their sides and unsecured on the remaining side, said detachable cuff being adapted to be folded over on a line substantially parallel with the unsecured edges, and the two layers of material being provided with independent button openings therethrough on opposite sides of the line of fold, said detachable cuff being adapted for application with the sleeve cuff fitted between the layers of material at the unsecured edges up to the fold with the button openings in line with the button openings of the sleeve cuff, one of said layers of material being cut away adjacent the edge intermediate the button openings, with the cut away area extending approximately from the button hole at one end of the cuff to the button hole at the other end of the cuff to reduce the thickness of the materials when the cuff is in place.

3. A detachable cuff of the double fold type for application to a shirt sleeve cuff, comprising two layers of material of substantially cuff shape secured together at their ends and along one side and unsecured on the remaining side, said detachable cuff being adapted to be folded over on a line substantially parallel with the unsecured side, and this unsecured side serving as a pocket to receive the shirt sleeve cuff for insertion down to the line of fold, the two layers of material being provided with independent button openings therethrough adjacent opposite edges on the unsecured side and having button openings formed through the two fabrics jointly on the opposite side of the line of fold, all of the button holes being positioned to align with ordinary located button holes in the shirt sleeve cuff, and one of said layers of material being cut away adjacent the unsecured edge intermediate the button openings, with the cut away area extending approximately from the button hole at one end of the cuff to the button hole at the other end of the cuff to reduce the thick-

ness of the materials fitted in place upon the shirt sleeve cuff.

In testimony whereof I hereunto affix my signature.
